UNITED STATES PATENT OFFICE.

BUSSELL HUFF, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

PRESSURE-REGULATOR FOR INTERNAL-COMBUSTION ENGINES.

992,505.

Specification of Letters Patent. Patented May 16, 1911.

Application filed August 23, 1907. Serial No. 389,883.

To all whom it may concern:

Be it known that I, RUSSELL HUFF, a citizen of the United States, and residing at Detroit, Wayne county, Michigan, have invented certain new and useful Improvements in Pressure-Regulators for Internal-Combustion Engines, of which the following is a specification.

My invention relates generally to internal combustion engines, and particularly to the means for supporting the automatic pressure valve which is sometimes used in such engines.

On some motor vehicles, particularly of the runabout type, it is necessary to locate the gasoline tank so low that it is impossible to supply the gasoline to the engine by gravity, and therefore some automatic pressure system must be employed. In such motor vehicles there has been employed an automatic pressure valve connected with the exhaust from the engine, whereby that exhaust furnishes the motive power for forcing the gasoline under uniform pressure to the engine. In such systems the automatic pressure valve has ordinarily been mounted either upon the dash-board of the machine, or upon the frame of the engine, and this pressure valve has been connected by pipes to the exhaust from the engine.

The object of the present invention is to provide a simple compact and convenient means for supporting the pressure valve and at the same time connecting it with the exhaust.

Another object is to include in the supporting means a simple and efficient form of strainer through which the exhaust must pass before it reaches the pressure valve.

With these objects in view my invention consists in a hollow angular bracket adapted to be mounted upon and connected with the exhaust pipe of the engine, and also connected directly to the automatic pressure valve, whereby that valve is not only conveniently supported, but is supplied from the exhaust.

It also consists in the strainer inserted in the bracket at the point where it makes its angular bend.

In the drawing my improved bracket and the exhaust pipe are shown in section, and the automatic pressure valve connected therewith is shown in elevation.

In the drawing, the part marked 1 is the exhaust pipe of the engine which is provided with a boss 2 surrounding an opening in the pipe. Mounted upon this boss and connected thereto in any suitable manner is the bracket 3 which is tubular in form, the interior being of two diameters, the diameter of the lower part being less than that of the upper part. Extending up through the opening in the exhaust pipe and into the lower part of the bracket 3 is the pipe 4, the lower end of which may be bent so as to face in the direction from which the exhaust from the engine comes. This bend in the pipe is not necessary, but when used it is for the purpose of more effectively receiving and conveying to the pressure valve the impulses due to the exhaust of the engine. The upper end of the bracket 3 is provided with screw threads 5 which receive corresponding screw threads on the tubular plug 6. This tubular plug 6 is closed at its upper end, is provided with a flange 7 which fits on top of the bracket 3, and is also provided with the angular projection 8 for the purpose of facilitating its removal. The tubular portion below the closed end is provided with perforations or openings 9, and the lower end of this tubular plug fits closely a shoulder 10 on the interior of the bracket 3. Within this plug 6 and conforming to its shape is the foraminous screen 11 which may be made of wire gauze, or finely perforated sheet metal.

Connected with the upper part of the bracket 3 and preferably made integral therewith is the part 12 of the bracket which furnishes the passage for the exhaust to the automatic pressure valve 13. The part 12 is connected to the pressure valve by the machined joint 14, 15 and the bolt 16. The particular form of the pressure valve is not shown, since it forms no part of the present invention. The invention is applicable to various forms of pressure valves. The part 12 may be placed at any angle to the part 3 which seems most convenient in the particular arrangement of parts of the engine with which it happens to be used.

It is believed that the purpose, function and operation of the bracket, as well as its advantages, will be obvious from the above description of the construction. Its purpose is to simplify and improve the connection

between the pressure valve and the exhaust. The purpose of the strainer is to remove the carbon and other impurities in the exhaust gas as it passes to the pressure valve, and 5 the advantage of the particular form shown is its simplicity and effectiveness.

What I claim is:

1. In an internal combustion engine, the combination with the engine exhaust pipe, 10 of a hollow bracket thereon and communicating therewith, a removable plug arranged in an opening of said bracket, a screen carried by the plug and extending across the passage through the bracket, a tube extending 15 from the interior of said bracket for a distance into the exhaust pipe and having an opening into which the exhaust is directed, and an automatic pressure valve communicating with the interior of the bracket, 20 for the purpose set forth.
2. In internal combustion engines, the combination with the engine exhaust pipe, of a hollow angular bracket mounted thereon and communicating therewith, a tubular 25 plug with closed outer end arranged in bracket at the angular bend thereof, the said plug having openings in its sides and having within it a foraminous screen, and an automatic pressure valve carried by said bracket and communicating with the interior 30 thereof.

3. In a bracket for use on internal combustion engines, the combination with two tubular parts rigidly connected together at an angle, of a tubular plug having its outer end closed and its sides perforated entering 35 one of said tubular parts at the angular bend of the bracket, and an internal shoulder on said part against which the inner end of said tubular plug fits.

4. In a bracket for use on internal combustion engines, the combination with two tubular parts rigidly connected together at an angle, of a tubular plug having its outer end closed and its sides perforated entering 40 one of said tubular parts at the angular bend of the bracket, a screw threaded connection between said plug and bracket, an angular projection on the plug for facilitating removal, a foraminous screen fitting 45 within the tubular plug and covering the perforations in the sides thereof, and an internal shoulder on said tubular part of the bracket against which the inner end of said tubular plug fits.

In testimony whereof I affix my signature in presence of two witnesses.

RUSSELL HUFF.
